UNITED STATES PATENT OFFICE.

CHARLES M. MACNAMARA, OF BRIDGETON, GLASGOW, SCOTLAND.

CRANE.

Application filed October 29, 1920. Serial No. 420,336.

To all whom it may concern:

Be it known that I, CHARLES MICHAEL MACNAMARA, a subject of the King of Great Britain and Ireland and the Isle of Man, 5 and a resident of Bridgeton, Glasgow, Scotland, have invented new and useful Improvements in and Relating to Cranes, of which the following is a specification.

This invention has reference to improvements in and relating to cranes and the like and comprises automatically acting means for tipping the bucket thereof.

According to this invention the bucket is provided with dogs or equivalent locking means, which, when the bucket is being raised prevent same from tipping. Suspended from or secured to the jib of the crane or the like is a member which, through suitable intermediate means actuates and 20 disengages said locking means and thereby permits the bucket to tip.

Preferably said member also acts as a guide which ensures that the bucket will turn only in the desired plane.

Under one arrangement the member would comprise what we term a crown piece which is suspended from the jib of the crane. This crown piece when the bucket is raised actuates through suitable 25 links or levers or a combination thereof the said locking means and thus permits the bucket to tip.

Under another arrangement, suspended and pivotally secured to the jib is a rigid member having a hooked shaped lower extremity. The said rigid member is actuated so that when the bucket is raised, the hooked extremity is below the linkwork or the like actuating the locking means. This 35 linkwork, when the bucket is slightly lowered is engaged and thereby raised by said hooked extremity, thus disengaging the locking means and permitting the bucket to tip.

The empty bucket would then be slightly raised, the hook or hooks moved clear of the linkwork or the like and the bucket lowered to be reloaded.

The movement of said framework may 50 be actuated automatically by the raising and lowering of the jib or moved manually or automatically in a manner hereafter described.

The bucket is preferably so constructed 55 that when full it will tilt when the locking

means are disengaged and when empty will automatically right itself. This is accomplished by placing the trunnions or the axis about which the bucket turns at a level slightly higher than the centre of gravity 60 of the bucket when empty and shaping the bucket so that it has a greater capacity above said axis than below. By this means the bucket when full always tends to tilt but when empty as the trunnions are located as aforesaid, it automatically rights itself.

For a complete understanding of this invention reference is had to the accompanying drawings wherein illustrative but preferred embodiments of the invention are disclosed and wherein—

Figure 1 is a front elevation illustrating a bucket and means of the suspended crown piece type for disengaging the locking 75 means.

Figure 2 is an end elevation of Figure 1.

Figure 3 is a view corresponding to Figure 2 but showing the crown piece and disengaging gear in contact.

Figure 4 is a larger view of the bucket and crown piece, the latter being shown partly in section.

Figure 5 is an end view of Figure 4, also partly in section.

Figure 6 is a fragmentary plan view showing the locking mechanism.

Figures 7 to 10 illustrate a bucket and disengaging gear of the suspended hook type, Figure 7 being an elevation of the 90 bucket and suspended rigid member the latter being shown in the position it would occupy before being moved below the disengaging gear. Figure 8 is an end view of Figure 7.

Figure 9 is a view corresponding to Figure 7 but showing the hooked extremity moved forward.

Figure 10 illustrates a view corresponding to Figure 9 but showing the bucket lowered to actuate the disengaging gear.

Referring now to the drawings for a detailed description of the constructions therein shown and first to Figures 1 to 6 inclusive:

A is the bucket, B the supporting frame or handle, C the crown piece and D the jib of the crane or the like. e are two dogs carried by the frame B and engaging corresponding notches in the lip of the bucket

when the latter is being raised as shown in Figure 1, 2, 4, 5 and 6. When engaging said notches it will be obvious that the bucket is prevented from tipping. The lower ends of said dogs are bifurcated, see Figure 6, so as to embrace the frame B and the upper ends thereof are pivotally secured to the outer ends of the links *f*. These links are provided with pivot pins *f'* intermediate their ends for pivotally supporting them between the two cross bars *g* secured to the frame B. One of said bars is omitted in Figure 4, for clearness of disclosure.

Pins secured to the inner ends of said links *f* pass through slots *h* in a plate *i* secured to a rod *j*.

The bucket is carried by a hook at the lower end of a torpedo shaped member *t* carried by the usual rope or chain *k* passing over the pulley *l* at the end of the jib D.

The crown piece C comprises a cylindrical member suspended by two ropes or chains *m* passing over the pulleys *o* preferably in alignment with the pulley *l*. Located in the interior of said cylinder is a second cylinder *p* cut preferably as shown in Figures 4 and 5 so as to form an inclined plane or guiding surface *q*. Alternatively such surface *q* may be made integral with the outer cylinder.

An angle *r* surrounds the foot of the said outer cylinder and short guiding links *s* connect the dogs *e* to the frame B.

The operation of this arrangement is as follows:

The crown piece is first adjusted to the required height.

When the bucket is raised the torpedo shaped member *t* enters the crown piece and the rod *j* comes in contact with the lower face of the angle iron *r* and is consequently depressed. This motion it transfers to the links *f*, which, turning about their pivots, raise the dogs *e* clear of the notches and thereby permits the bucket to tilt.

It is usually desirable that the bucket should tilt in a given plane and to ensure this the projecting end of the pin *u*, which passes through the end of the torpedo shaped member *t*, and by which the chain or rope is secured thereto, bears against the guiding surface *q* when the bucket is nearly fully raised and is guided into the slot *n* at the end of the guiding surface. When being so guided the said projecting end turns the member *t* and thereby also the bucket A in a horizontal plane to the required tipping position.

Should it be required to alter the plane in which the bucket tips this may be accomplished by turning the crown piece bodily or alternatively the inner cylinder only through the required angle.

If desired in order to prevent or minimize any turning moment being imparted to the

crown piece by the bucket the pulleys *o* may be placed further apart than illustrated in the drawings and preferably the crown piece would be suspended as near to the tip of the jib as possible. The lower end of the crown piece may be of elliptical or equivalent shape as shown to accommodate the upper end of the frame B.

Alternatively instead of the crown piece being held stationary and the rod *j* brought into contact therewith, the said crown piece may be allowed to suddenly descend and strike the rod.

The invention will now be described with reference to the modification illustrated in Figures 7 to 10.

The bucket A is provided with the usual frame or handle B which latter is provided with locking dogs *l*. Said dogs, when the bucket is being raised, engage corresponding notches 2 in the lip of the bucket which is thereby prevented from tipping. The dogs are connected to a frame 3 which is preferably shaped as illustrated to follow the contour of the bucket frame B which latter acts as a support and guide.

The bucket is suspended by a hook secured to a cone, torpedo or like shaped member 4 which in turn is connected to the usual rope or chain 5 which passes over the pulley 6 of the jib D.

Suspended from and pivotally secured to the jib D is a frame 7 whose lower end is hooked, and which, as will be hereafter explained, actuates the frame 3 to disengage the dogs 1. Preferably said hooked extremity comprises a plate 8 of U cross section and having its sides wedge shaped to form, as shown also at *q* in Figs. 4 and 5, inclined cam faces as illustrated.

10 is a rope or equivalent means by which the hooked extremity of the frame is moved towards the rope 5 against the action of a counter poised weight 9. The operation of this modification is as follows:

The bucket is loaded and raised, being prevented from tipping by the dogs 1. During this operation the hooked extremity 8 is moved towards the rope 5, the latter and the member 4 passing between the two sides of the plate 8. This latter acts as a guide for the upcoming frame B which bears on the inclined cam faces of the plate 8 and is turned so as to lie in the required plane. This ensures that the frame 3 will engage properly with the hooks of plate 8 and also that the bucket will tip in the desired plane. When the bucket has reached the position shown in Figure 9, i. e., when the frame 3 is over the hooks of the plate 8, it is then lowered to the position shown in Figure 10. This causes the frame 3 to come in contact with the hooks and consequently to be raised. By this means the dogs are disengaged and the bucket allowed to tip.

The empty bucket would then be raised slightly to clear the hooks, the latter moved clear of the rope and the bucket again lowered to be reloaded. The movement of the 5 hooked extremity 8 of the frame 7 towards and away from the rope may be accomplished in various ways.

For example, a rope 10 or the like would be secured to an upward extension of the 10 frame 7 as shown, and the other end thereof to any suitable part of the crane or winch. In operation under this arrangement the loaded bucket is first raised as usual and subsequently the jib is also raised. This latter 15 movement moves the hooks towards the chain 5. To free the bucket from the hooks the former is first raised slightly and the jib lowered thus permitting the hooks to move clear of the rope under the action 20 of the weight 9.

The length of the rope 10 would preferably be such that when the jib is raised to the necessary height, the chain 5 is passing between the hooks. Of course instead of the 25 pivoted hooks being brought towards and freed from the chain by the movement of the jib, this operation may be performed separately by hand through any suitable means.

The type of bucket used is preferably that 30 which will now be described with particular reference to Figure 4.

The trunnions v are so positioned that the axis $x-x$ about which the bucket rotates or tips is above the centre of gravity of the 35 bucket when empty, so that after tipping the bucket rights itself. The capacity of the bucket above the line $x-x$ is greater than that below said line, so that when full the centre of gravity of the bucket and con- 40 tents is above the axis.

Therefore when full the bucket would always tend to tip or rotate about its axis.

As many changes could be made in the above construction and many apparently 45 widely different embodiments of this invention could be made without departing from the scope thereof, it is intended that all matter contained in the above description or shown in the accompanying drawings shall 50 be interpreted as illustrative and not in a limiting sense.

It is also to be understood that the language to be used in the following claims is intended to cover all of the generic and 55 specific features of the invention herein described and all statements of the scope of the invention, which, as a matter of language, might be said to fall therein.

What I claim and desire to secure by Let-

60 ters Patent is:—

1. In a hoisting apparatus, in combination, a hoisting bucket, hoisting means for said bucket, means for holding said bucket in load-carrying position, and means de- 65 pendent upon operation of the hoisting

means for automatically turning said bucket, so it may be tipped in a desired plane.

2. In a hoisting apparatus, in combination, a hoisting bucket, hoisting means for said bucket, means for holding said bucket 70 in load-carrying position, means dependent upon operation of the hoisting means for automatically moving said bucket so it may be tipped in a desired plane, and means for subsequently releasing said holding means. 75

3. In a hoisting apparatus, in combination, a hoisting bucket, hoisting means for said bucket, means for holding said bucket in load-carrying position, means dependent upon operation of the hoisting means for 80 automatically releasing said holding means, and means for automatically turning said bucket so it may be tipped in a desired plane.

4. In a hoisting apparatus, in combination, a hoisting bucket, hoisting means for 85 said bucket, means for holding said bucket in load-carrying position, means dependent upon operation of the hoisting means for automatically turning said bucket so it may be tipped in a desired plane upon elevation 90 thereof, and means for subsequently automatically releasing said holding means.

5. In a hoisting apparatus, in combination, a hoisting bucket, hoisting means for said bucket, means for holding the bucket in 95 load-carrying position, means dependent upon operation of the hoisting means for automatically turning said bucket so it may be tipped in a desired plane, means for automatically releasing said holding means 100 when said bucket is raised to a predetermined position and means whereby said bucket moves automatically to dumping position.

6. In a hoisting apparatus, in combination, a hoisting bucket, hoisting means for said bucket, means for holding said bucket in load-carrying position, means for automatically releasing said holding means at a 110 predetermined point in the travel of the bucket and means operable prior to the release of said holding means for automatically turning said bucket on a vertical axis.

7. In a hoisting apparatus, in combination, a hoisting bucket, a hoisting rope for said bucket, means for holding said bucket in load-carrying position and means adjacent said rope and adapted to contact with said holding means at a predetermined point in the elevation of the bucket for releasing the latter and allowing it to tip to dumping position, and means associated with said releasing means to automatically swing said bucket on a vertical axis prior to the release 115 of said holding means.

8. In a hoisting apparatus, in combination, a jib, a hoisting bucket carried in suspension by said jib, means for raising and lowering said bucket, means carried by said jib adapted to automatically align said 120 125

- bucket while the latter is being raised and automatic means for subsequently causing said bucket to be dumped.
19. In a hoisting apparatus, in combination, a hoisting bucket, hoisting connections for said bucket and means co-operating with said connections for automatically positioning the bucket during raising movement thereof.
- 10 20. In a hoisting apparatus, in combination, a hoisting bucket, hoisting connections for said bucket, including a block, a member supported adjacent said hoisting connections and adapted to co-operate with said block to swing said bucket into a predetermined dumping position.
- 25 20. In a hoisting apparatus, in combination, a hoisting bucket, hoisting connections for said bucket, including a block, a member supported adjacent said hoisting connections, said block and member having complementary formations adapted to interengage as the bucket is raised to automatically position the latter in dumping position.
- 25 30. In a hoisting apparatus, in combination, a hoisting bucket, hoisting connections for said bucket, including a block, a member supported adjacent said hoisting connections and a projection and cam surface associated with said block and member adapted to co-operate as the bucket is raised to automatically position the latter in dumping position.
- 35 35. In a hoisting apparatus, in combination, a bucket having supporting means pivotally connected thereto, means for locking said bucket stationary with respect to said supporting means including members carried by said supporting means adapted to engage parts of said bucket and readily disengageable therefrom, links pivotally connected to said members and an actuating trigger loosely connected to said links.
- 40 45. In a hoisting apparatus, in combination, a jib, a bucket, supporting means for said bucket carried by said jib and vertically movable with respect thereto, a guide carried by said jib independently of said supporting means and means comprising a tubular member having a cam face adapted to contact with a part of said supporting means thereby to rotate said bucket on its vertical axis into a predetermined position during elevation thereof, said face terminating in a slot adapted to register with said co-operating part upon subsequent elevation of said bucket.
- 50 55. In a hoisting apparatus, in combination, a hoisting bucket, means for locking said bucket in load carrying position, means for automatically turning said bucket, dependent upon travel thereof, for tipping in a predetermined plane, means for holding said bucket in said predetermined plane and means operating subsequently to said holding means for releasing said locking means.
16. In a hoisting apparatus, in combination, a hoisting bucket, means for locking said bucket in load carrying position, means for automatically turning said bucket, dependent upon travel thereof, for tipping in a predetermined plane, means for holding said bucket in said predetermined plane, and means for releasing said locking means, said positioning means, holding means, and locking means functioning sequentially during a hoisting operation of said bucket.
17. In a hoisting apparatus, in combination, a hoisting bucket having a notch, a supporting bail attached to said bucket, and a latch mounted upon said bail and adapted to seat in said notch for holding said bucket in load carrying position, said latch having a bifurcation cooperating with said bail to transmit locking thrusts thereto from the notch of the bucket.
18. In a hoisting apparatus, in combination, a tilting hoisting bucket, a supporting bail attached to said bucket, a latch mounted for bodily movement on said bail for holding said bucket in load carrying position, and automatic means operative upon travel of the bucket to release said latch so as to permit said bucket to tilt.
19. In a hoisting apparatus, in combination, a hoisting bucket, a supporting bail attached to said bucket, a bodily movable latch for holding said bucket in load carrying position, an operating rod carried by said bail and operatively connected to said latch, and means for operating said rod in different angular positions of said bail.
20. In a hoisting apparatus, in combination, a hoisting bucket, a supporting bail attached to said bucket, a rigid bodily movable latch member for holding said bucket in load carrying position and having a bifurcation cooperating with said bail, an operating rod carried by said bail and operatively connected with said latch, and means for automatically operating said rod in different angular positions of said bail.
21. In a hoisting apparatus, in combination, a tilting hoisting bucket, a supporting bail attached to said bucket, a latch bar mounted for bodily movement on said bail for holding said bucket in load carrying position, said latch bar having a latching terminal for simultaneous engagement with said bail and bucket to resist tilting movement of the latter in either direction.
22. In a hoisting apparatus, in combination, a tilting hoisting bucket, a supporting bail attached to said bucket, a latch bar mounted for bodily movement on said bail for holding said bucket in load carrying position, said latch bar having a latching terminal for simultaneous engagement with said bail and bucket to resist tilting movement of the latter in either direction, a latch

tripping rod carried by said bail, and a tripping member for engagement with said rod in different angular positions of the bail for automatically tripping said latch upon movement of the bucket.

23. In a hoisting apparatus, in combination, a hoisting bucket, a hoisting mechanism having a single hoisting rope attached to said bucket for raising and lowering the same, and means dependent upon operation of said hoisting mechanism for automatically turning said bucket so it may be tipped in a desired plane.

24. In a hoisting apparatus, in combination, a hoisting bucket, a hoisting mechanism having a single hoisting rope attached to said bucket for raising and lowering the same, means dependent upon operation of said hoisting mechanism for automatically turning said bucket so it may be tipped in

a desired plane, and means for stopping the bucket in the desired plane and holding it there during dumping of its contents.

25. In a hoisting apparatus, in combination, a hoisting bucket, a hoisting mechanism having a single hoisting rope attached to said bucket for raising and lowering the same, means dependent upon operation of said hoisting mechanism for automatically turning said bucket so it may be tipped in a desired plane, said turning means including a cam and cooperating lug, said cam merging into a seat which cooperates with said lug for stopping said bucket in the desired plane and holding it there during dumping of its contents.

CHAS. M. MACNAMARA.
